CLAIM

The ornamental design for a notebook computer housing, as shown and described.

DESCRIPTION

FIG. 1 is a perspective view of a notebook computer housing according to our design shown in a closed configuration; FIG. 2 is a top view thereof;

FIG. 3 is a bottom view thereof;

FIG. 4 is a front view thereof;

FIG. 5 is a back view thereof;

FIG. 6 is a right side view thereof;

FIG. 7 is a left side view thereof;

FIG. 8 is a perspective view thereof shown in an open configuration;

FIG. 9 is a top view thereof;

FIG. 10 is a bottom view thereof;

FIG. 11 is a front view thereof;

FIG. 12 is a back view thereof;

FIG. 13 is a right side view thereof;

FIG. 14 is a left side view thereof;

FIG. 15 is a perspective view of a second embodiment thereof shown in a closed configuration;

FIG. 16 is a top view thereof;

FIG. 17 is a bottom view thereof;

FIG. 18 is a front view thereof;

FIG. 19 is a back view thereof;

FIG. 20 is a right side view thereof;

FIG. 21 is a left side view thereof;

FIG. 22 is a perspective view thereof shown in an open configuration;

FIG. 23 is a top view thereof;

FIG. 24 is a bottom view thereof;

FIG. 25 is a front view thereof;

FIG. 26 is a back view thereof;

FIG. 27 is a right side view thereof; and,

FIG. 28 is a left side view thereof.

Broken lines are shown for environmental purposes only and form no part of the claimed design.
